CLAMPING MEANS FOR WINDSHIELD
DEICER PANELS

John Harold Webster, Rocky Hill, Conn., assignor
to The Stanley Works, New Britain, Conn., a
corporation of Connecticut

Application August 21, 1944, Serial No. 550,475

9 Claims. (Cl. 292—241)

1

This invention relates to a de-icer panel for an airplane windshield, and more particularly to improved double-acting clamping means for holding said panel tightly against said windshield in order to prevent air leakage from said panel, and also to prevent vibration and rattling.

One object of the present invention is to provide a de-icer panel clamping means of the above nature including a strike and a latch member which will permit the panel to be readily attached to and detached from the windshield.

A further object of the invention is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawing,

Fig. 1 represents a rear view of the improved clamping means as it appears when in assembled position for holding a de-icer panel upon a windshield frame.

Fig. 2 is a longitudinal sectional view of the same, taken along the line 2—2 of Fig. 1, looking in the direction of the arrows, and showing the interior construction of the latch member.

Fig. 3 is a transverse sectional view of the same, taken along the line 3—3 of Fig. 1, and showing the appearance of the latch and strike member in locked position.

Fig. 4 is a detail sectional view of the same taken through the latch blade along the line 4—4 of Fig. 1.

Referring now to the drawing in which like reference numerals denote corresponding parts throughout the several views, the numeral 10 indicates a rectangular windshield frame having a transparent pane 11 which is mounted in an upper horizontal rail 12, a lower horizontal rail, and side rails, not shown.

In order to prevent the collection and accumulation of sleet, ice, or snow on the front of the windshield which might obstruct the vision of the airplane pilot, provision is made of a rectangular de-icer panel having an upper horizontal rail 13, which for convenience in assembly, has an open semi-circular recess 14 for embracing a latch stud 27 of the clamping means to be hereinafter described.

The de-icer panel is provided with a transparent pane 15, which has a rectangular notch 16 for

2

receiving a latch casing 17. It will be understood that the transparent panes 11, 15 may be made of glass or any suitable molded plastic material.

The casing 17 is provided with a pair of offset end feet 18, 19 adapted to underlie the pane 15, as clearly shown in Fig. 2. The latch casing 17 has on one side a stop lug 20, and on its other side a flange 21 to limit the swinging of the latch blade 33, to be described later.

The casing 17 has a central bearing hole 22 in the upper part thereof for tightly fitting about a reduced end 24 of a horizontal sleeve member 23, said latch casing also having a rear cover plate 25 which has a bearing hole 26 fitted tightly about the reduced section 24 of the sleeve 23.

Provision is also made of a horizontal latch stud 27 having a reduced cylindrical bearing section 28 which is shaped to fit within the reduced end 24 of the sleeve 23, said stud 27 also having a still further reduced squared forward end 29 for receiving the latch blade 33 which is adapted to swing in a vertical plane.

The rear end of the latch stud 27 has a narrow slot 30 which is adapted to fit tightly about a flat handle 31 which is secured in said slot by means of a pin 32. The blade 33 has a square hole 34 fitting over the reduced squared end 29 of the latch stud, said blade having a pair of parallel beveled side edges 35, 36 and a curved end edge 37, the latter of which is adapted to engage a U-shaped leaf spring 44 secured to a strike plate 40, as hereinafter described.

The reduced end 24 of the sleeve 23 rests upon a washer 38 preferably formed of fiber, which is adapted to serve as an abutment for the latch blade 33.

Strike member

The strike member, which cooperates with the latch, comprises the strike plate 40 which is preferably made rectangular in shape, and has a pair of slots 41, 42 in its upper edge which serve to receive screw bolts 42a, 42b on which nuts 42c, 42d are screwed for detachably clamping the strike member to the upper rail 12 of the windshield frame 10 in such a manner as to permit vertical adjustment of said strike plate 40 with respect to said frame 10.

The strike plate 40 is provided with a short upper rearwardly extending central narrow flange 43 to which is secured as by rivets 46, 47, the vibration-preventing U-shaped leaf spring 44, previously mentioned. The spring 44 has a flat short upper end 45, and an elongated arched lower end 48 shaped to fit the curved end edge

37 of the latch blade 33. The extremity 49 of the lower end 48 of the leaf spring 44 is upturned to serve as a guide to cause the latch blade 33 to move into proper engagement with the arched lower end 48 of said spring 44.

The strike plate 40 is provided on its lower side with a wide horizontal flange 52 extending the entire length of said plate 40, said flange 52 having struck out therefrom an inclined resilient wedge cam 50, leaving a slot 51 between said wedge cam 50 and the base of said strike plate 40 for receiving the latch blade 33, as most clearly shown in Fig. 3.

In order to prevent the escape of hot air, provision is made of a felt strip 53 located between the upper rail 13 of the panel and the windshield pane 11.

While only one clamping means is illustrated on the drawing, it will be understood that any number of strikes and associated latches may be located on either or both of the top and bottom rails of the windshield frame and de-icer panel respectively.

The present invention is of especial importance where a de-icer panel is used which has an air inlet slot at the bottom, in which case the U-shaped leaf spring 44 not only serves to prevent vibration but also forces the lower edge of the panel down against the lower end of the windshield frame adjacent the air intake manifold located on the cowl of the airplane.

Operation

In operation, assuming the strike plate has first been assembled on the windshield frame 10 in the proper adjusted position, when it is desired to lock the panel to said frame, said panel will first be pressed against the windshield pane 11 in proper position between the upper and lower rails of the windshield frame 10. The handle 31 of each latch stud 27 will then be turned from vertical to horizontal position, as shown in Figs. 1 and 3, causing the latch blade 33 to move to the vertical position, as shown, into engagement with the lower arched section 48 of the U-shaped spring 44. This will cause each spring 44 to exert a compressive force against the panel to prevent rattling and vibration. At the same time each latch blade 33 will be pressed outwardly by means of the coiled spring 39 against the resilient wedge cam 50 on the strike plate 40, this action causing the panel to be pressed tightly against the windshield for preventing leakage of air around the edge of the felt strip 53.

While there has been disclosed in this specification one form in which the invention may be embodied, it will be understood that this form is shown for the purpose of illustration only, and that the invention is not to be limited to the specific disclosure, but may be modified and embodied in various other forms without departing from its spirit. In short the invention includes all the modifications and embodiments coming within the scope of the following claims.

Having thus fully described the invention, 65 what is claimed as new, and for which it is desired to secure Letters Patent is:

1. In a double-action device for clamping the edge of a de-icer panel to a windshield frame, a U-shaped strike plate mounted horizontally on the edge of said frame, said plate having rearwardly extending upper and lower flanges, a U-shaped leaf spring having one leg thereof secured to said upper flange, said lower flange having a horizontal slot provided with a resilient wedge cam.

cam, said panel carrying an initially horizontal pivoted latch blade, and means to swing said latch blade to vertical position for causing said blade to simultaneously engage the lower leg of said spring and said wedge cam.

2. In a device for clamping the edge of a de-icer panel to a windshield frame, said windshield and said panel both having transparent panes, a strike plate mounted on the edge of said frame and having an upper compression spring and a lower flange provided with a resilient wedge cam slot, a latch member for cooperating with said strike plate comprising a casing secured to the edge of said panel, a sleeve fitted into said casing, a central stud fitted into said sleeve, said stud having a handle at one end located behind the panel and having a clamping blade on its other end, said blade being adapted to be swung to vertical position into simultaneous engagement with said compression spring and said wedge cam to prevent rattling and leakage respectively.

3. The invention defined in claim 2, in which provision is made of a coiled spring housed in said sleeve to press said blade against the edge of said wedge cam slot.

4. The invention defined in claim 2, in which said casing has means to limit the swinging of said blade in both directions.

5. In a double-action device for clamping the edge of a panel to a frame, a U-shaped strike plate mounted on the edge of said frame, said plate having rearwardly-extending upper and lower flanges, a U-shaped leaf spring having one leg thereof secured to said upper flange, said lower flange having a horizontal slot provided with a resilient wedge cam, said panel carrying an initially horizontal pivoted latch blade, and means to swing said latch blade to vertical position for causing said blade to simultaneously engage the lower leg of said spring and said wedge cam.

6. In a double-action device for clamping the edge of a panel to a frame, a U-shaped strike plate mounted horizontally on the edge of said frame, said plate having rearwardly-extending upper and lower flanges, a U-shaped leaf spring having one leg thereof secured to said upper flange, said lower flange having a horizontal slot provided with a resilient wedge cam, said panel carrying an initially horizontal pivoted latch blade, means to swing said latch blade to vertical position for causing said blade to simultaneously engage the lower leg of said spring and said wedge cam, and means for detachably and adjustably securing said strike plate to the edge of the windshield frame.

7. In a double-action device for clamping the edge of a panel to a frame, a U-shaped strike plate mounted on the edge of said frame, said plate having rearwardly-extending upper and lower flanges, a U-shaped leaf spring having one leg thereof secured to said upper flange, said lower flange having a slot provided with a resilient wedge cam, said panel carrying a pivoted latch blade, and means to swing said latch blade to locking position for causing said blade to simultaneously engage the lower leg of said spring and said wedge cam, said strike plate being provided with a plurality of open slots in the edge of its base to receive screw bolts having nuts threaded thereon for attaching said strike plate to said frame and permit said strike plate to be removed therefrom by merely loosening said nuts without removing said bolts, said strike

plate being removable from said frame by moving it inwardly from the edge of said frame.

3. In a double-action device for clamping the edge of a panel to a frame, a strike plate for mounting on the edge of said frame and having a compression spring located adjacent the outer edge of said strike plate, the inner edge of said strike plate being provided with a resilient wedge cam slot, a latch member for cooperating with said strike plate comprising a casing having a pair of opposed offset feet for engagement with said panel, a sleeve fitted into said casing, and a central stud fitted into said sleeve, said stud having a handle on one end projecting therefrom and spaced from said panel, said stud also having a clamping blade on its opposite end for simultaneously engaging said compression spring and wedge cam to prevent rattling and leakage respectively.

9. In a double-action device for clamping the edge of a panel to a frame, a strike plate for mounting on the edge of said frame and having a compression spring located adjacent the outer edge of said strike plate, the inner edge of said strike plate being provided with a resilient wedge cam slot, a latch member for cooperating with said strike plate comprising a casing for engagement with said strike plate, a sleeve fitted into said casing, and a central stud fitted into said sleeve, said stud having a handle on one end projecting therefrom and spaced from said panel, said stud also having a clamping blade on its opposite end for simultaneously engaging said compression spring and wedge cam to prevent rattling and leakage, respectively, said handle being located at right angles to the position of said latch blade.

JOHN HAROLD WEBSTER.
